[57] **CLAIM**

The ornamental design for a fluorescent lighting fixture, as shown and described.

DESCRIPTION

FIG. 1 is a bottom and end perspective view of a recessed direct and indirect fluorescent lighting fixture embodiment of my new design;

FIG. 2 is a bottom view thereof;

FIG. 3 is a first end view thereof;

FIG. 4 is a second end view, opposite from the first end view of FIG. 3;

FIG. 5 is a first side view thereof;

FIG. 6 is a second side view, opposite from the first side view of FIG. 5; and,

FIG. 7 is a top view thereof, opposite from the bottom view of FIG. 2.

FIGS. 1, 2, and 5-7 are broken away to indicate indeterminate length.
